US00D572593S

(12) **United States Design Patent**
Adler et al.

(10) **Patent No.:** US D572,593 S
(45) **Date of Patent:** ** Jul. 8, 2008

(54) **BOTTLE**

(75) Inventors: **Deborah B. Adler**, New York, NY (US);
Klaus Rosburg, New York, NY (US);
Patrick Douglas, Minneapolis, MN (US); **Matthew S. Grisik**, Rosemount, MN (US)

(73) Assignee: **Target Brands, Inc.**, Minneapolis, MN (US)

(**) Term: **14 Years**

(21) Appl. No.: **29/277,823**

(22) Filed: **Mar. 9, 2007**

Related U.S. Application Data

(63) Continuation of application No. 29/221,974, filed on Jan. 25, 2005, now Pat. No. Des. 542,661.

CLAIM

The ornamental design for a bottle, as shown and described.

DESCRIPTION

FIG. 1 is a top, right side, and rear perspective view of a bottle of the present invention, with a label and a card insert removed for ease of illustration;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, left side, and front perspective view of a second embodiment showing the bottle of FIG. 1 with a neck ring;

FIG. 9 is a rear elevational view thereof;

FIG. 10 is a top, right side, and rear perspective view of a third embodiment showing a label applied to the bottle of FIG. 1;

FIG. 11 is a front elevational view thereof;

FIG. 12 is a top, right side, and rear perspective view of a fourth embodiment showing a label applied to the bottle of FIG. 1 and an added card insert in broken lines; and,

FIG. 13 is a right side elevational view thereof.

The broken lines shown in the drawings are for illustrative purposes only and form no part of the claimed design.
